UNITED STATES PATENT OFFICE.

LELAND L. ODOM, OF LITTLE ROCK, ARKANSAS, ASSIGNOR, BY DIRECT AND MESNE ASSIGNMENTS, TO M-O-R PRODUCTS COMPANY, A CORPORATION OF DELAWARE.

PROCESS FOR REMOVING SULPHUR COMPOUNDS FROM PETROLEUM OILS.

Application filed June 13, 1924. Serial No. 712,846.

The invention, broadly, relates to the distillation of petroleum oils. The primary object of the invention is the removal of sulphur compounds from the oil in distillation.

Other objects are to assist in the purification of oils, and to provide a process for the removal of sulphur compounds, which is extremely efficient, and inexpensive.

With these, and such other objects in view as will be apparent from the description, the invention resides in the novel process hereinafter described and claimed, an apparatus for carrying out the process being shown in the accompanying drawings in which;

The figure is an elevation, partly in section, of an apparatus arranged for carrying out the process.

Heretofore in this art, many attempts have been made to remove the sulphur compounds from petroleum oils, none of which have been successful in removing a major portion of the compounds. Furthermore the processes as now employed, are expensive in application, and of a low efficiency. In oils treated by my process, the sulphur is removed down to less than one fourth of one per cent.

As illustrated 10 comprises a steel still of approximately 300 barrels capacity, which is charged with crude petroleum oil, or such distillate or other liquids as desired for treatment. Rising from the still are a plurality of metallic cylindrical containers, preferably three in number, as 11, 12 and 13, having constricted bottoms in communication with the still by means of the pipes 14, 15 and 16. These pipes are provided with the valves 17, 18 and 19.

The upper end of container 11, at one end of the still, connects with a condenser line 20, and the upper ends of the containers 12 and 13 are also connected with the line 20 by means of the pipes 21 and 22 respectively. A valve 23 is provided in the condenser line 20 between containers 11 and 12, and a valve 24 is disposed in the line between the containers 12 and 13, for a purpose hereinafter described. A release line 25 is arranged between the still and condenser line for emergency purposes.

Each of the series of containers 11, 12 and 13, is filled with closely packed tightly compressed metallic wool, of a fine hair

like consistency, which is applied from the upper ends thereof, and packed therein to the desired consistency. If desired, the wool may be inserted in the form of cylindrical bales, bound with wire which is cut on insertion to allow the wool to expand and completely fill the containers. The constricted bottoms of the containers insure an efficient packing and compression of the wool at these points.

The essential feature of my process lies in the use of metallic wool. In operation, as the still is fired, valves 17, 23 and 24 are opened and valves 18 and 19 are closed. The hot oil vapors will then pass up through container 11 and to the condenser line for treatment in the usual manner. Due to the compression of the metallic wool in the container, the vapors will be forced into intimate contact with the entire surface of each shred of the wool and the sulphur contained in the oil fumes will combine with the metal of the wool to form sulphides and some sulphates. The rapidity of the reaction is accelerated by increase in temperature, and the process can be governed accordingly.

When approximately one third of the still content has been treated, valve 17 is closed and 18 is opened, permitting the vapors to pass up through the second container 12. Valve 23 in the condenser line is then closed to prevent back flow. In like manner, when the charge of wool in container 12 is found to have extracted its capacity of sulphur from the vapors passing therethrough, valve 18 is closed and 19 is opened to pass the vapors up through the container 13. Valve 24 in the condenser line is closed to prevent back flow.

I have found that copper wool gives the best results and in the preferred embodiment of my process I use copper wool of a fine, hair like consistency, closely and tightly packed and compressed. It is obvious that the greater the amount of wool employed, the greater will be the reaction, as a larger metallic surface will be exposed to the oil vapors. It is a matter of importance that the wool be tightly packed, as the vapors will then come into intimate contact with every particle of the metal.

While copper wool gives the best results, iron wool or steel wool may be employed, as well as the wool of any metal that com-

bines with sulphur under proper conditions of temperature. Among such may be mentioned, aluminum, zinc, lead.

In each and every instance where the wool of the metals referred to is employed, the petroleum vapors passing through and over the wool will be relieved of sulphur to a percentage considerably below one fourth of one per cent.

10 My process consists in passing petroleum vapors from a still, through and over metallic wool, preferably copper wool, to remove practically the entire sulphur content of the oil. Owing to the affinity of the sul-

15 phur for the metal, under heat, the sulphur will free itself of the oil and combine with the wool. This is a radical departure from the art. No other agents are employed for effecting the reaction, than metal in the state 20 of finely shredded, hair like wool, packed and compressed.

The charge of compressed metallic wool in the containers may be renewed as desired, and the removed wool treated in any desired

manner for recovery of the sulphur extract- 25 ed from the oil.

It is to be understood that the process is applicable to any liquid hydrocarbons and distillates of petroleum, the essential feature being the passage of the heated vapors of the 30 material in the still, through the metallic wool.

The temperature at which the sulphur of the oil vapors will combine with the wool varies with the metal employed and will be 35 regulated accordingly for the most efficient results.

I claim:—

In the distillation of petroleum oils, the removal of more than ninety nine and three 40 fourths percent of the sulphur content of the oils, by passing the still vapors through tightly packed and compressed copper wool, the fibers whereof are of an even and extremely fine hair like consistency. 45

In testimony whereof I affix my signature.

LELAND L. ODOM.
